(57) **CLAIM**

The ornamental design for a air-cooled metallic tubular horticulture light fixture, as shown and described.

DESCRIPTION

FIG. 1 is a top perspective view of the air-cooled metallic tubular horticulture light fixture, according to the new and unique ornamental design;

FIG. 2 is a right end view of the air-cooled metallic tubular horticulture light fixture as shown in FIG. 1, further showing the new design;

FIG. 3 is a front side view of the air-cooled metallic tubular horticulture light fixture as shown in FIG. 1, the back side being a mirror image thereof, further showing the new design;

FIG. 4 is a top side view of the air-cooled metallic tubular horticulture light fixture, as shown in FIG. 1;

FIG. 5 is a bottom side view of the air-cooled metallic tubular horticulture light fixture, as shown in FIG. 1;

FIG. 6 is a left end view of the air-cooled metallic tubular horticulture light fixture as shown in FIG. 1, further showing the new design; and,

FIG. 7 is a bottom perspective view of the air-cooled metallic tubular horticulture light fixture with a lamp installed, according to the new and unique ornamental design.
